HEATING TUBE

Frank W. Ofeldt, McKeesport, Pa., assignor to Homestead Valve Manufacturing Company, Coraopolis, Pa., a corporation of Pennsylvania

Application June 30, 1936, Serial No. 88,106

6 Claims. (Cl. 122—250)

This invention relates generally to heating tube structure and more particularly to heating tubes or coils for generating steam and vapors of liquid and the method of operating the same.

5 The invention may be conveniently applied to steam or vapor emulsion heaters for sprays and the like.

The present practice in the design of heating coils has been directed largely to the formation 10 of the coils to provide a baffling and a flue effect at the proper positions within the combustion chamber. Other designs have been produced to prevent excessive condensation within the combustion chamber by arranging the heating coil to expose the incoming or cold fluids to a lower 15 temperature than that applied to the fluid passing from the coil. This has been accomplished by feeding the fluid in a coil that leads from the top of the heater and circulates around the cooler portions of the combustion chamber before it becomes exposed to the highly heated portions. Again the coils are sometimes wound around the shell forming the combustion chamber so that the fluid therein may be preheated before it is circulated over or through the combustion chamber. Heating coils are frequently provided with radiating fins for increasing their effective heat 25 transmission.

These heating coils are usually arranged so 30 that their single or multiple passes may be drained from the bottom thereof. However during ordinary use they may stand full or partially full of fluid in readiness for the next operation, if they are designed for intermittent use. In coils of this character the vapor or steam formed therein collects at the top of the coil which forms a single chamber, which may be compared to that of a steam boiler.

The principal object of this invention is the 35 provision of a heating coil that, while having the advantages of the present art, is designed to provide a multiplicity of traps within the coil to prevent the vapor or steam from collecting in the upper portion when the fluid is not continuously 40 traveling through the coil.

This arrangement prevents the discharge of a 45 considerable quantity of vapor or steam from the heating coil when it is intermittently started but permits the discharge of a blend of the fluid in the form of a vapor or steam with the liquid of the fluid when the flow is reestablished.

This is especially advantageous where the fluid 50 comprises an emulsion of different fluids which, owing to their inherent characteristics, may segregate if permitted to stand a short while.

Another object of this invention resides in the manner in which the heating coils are positioned with respect to the burner.

This invention also includes the provision of a novel form of heating coil supporting means 5 within the combustion chamber.

Another object is the provision of a novel arrangement of a plurality of heating coils within the combustion chamber which effects an increasing capacity through the heating coils to 10 permit expansion of the fluid as it proceeds therethrough.

Other objects and advantages appear herein-after.

In the accompanying drawing I have illustrated 15 a practical embodiment of the principles of my invention:

Fig. 1 is a side elevation of a plurality of heating coils within a combustion chamber and showing diagrammatically an arrangement of a burner having associated apparatus, parts of which are broken away, disposed in proper relation with respect to the heating coils.

Fig. 2 is a front elevation of a heating coil having a portion of the front passes of the coil turns 20 shown in section.

Fig. 3 is a front elevation showing a part of 25 a heating coil with some of the front passes cut away and the rear passes of a few coil turns being in section.

Fig. 4 is a plan view showing a modification of 30 a heating coil arrangement wherein three coils are employed.

Referring to the drawing, 10 represents a combustion chamber supported on the base ring 11. 35 12 represents a heating coil formed in the shape of a helix from any suitable tubing. The upper end of the coil 12 is connected to one port of the junction block or fitting 13. 14 represents a second heating coil, the upper end of which is 40 connected to another port in the block 13, thereby forming a continuous passageway from the lower end of the coil 12 through the block 13 to the lower end of the coil 14.

The lower end of the coil 12 is arranged to be 45 connected to a source of fluid supply, not shown. The fluid supply may be from a single source or from separate sources. The pipe lines 15 and 16 represent the connections between separate sources of fluid supply and the fluid pumping 50 chambers 17 and 18 respectively of the displacement pump 19. The separate fluids may then be joined by a common discharge passage within the pump casing head. The fluid blend thus formed is pumped through the pipe 20, the check 55

valve 21, the pipe 22 to the lower end of the coil 12, thence up through the coil 12, the block 13, and down through the coil 14, to the discharge line 23. The end of the discharge line may be 5 provided with a suitable dispensing nozzle and/or valve depending upon the character of the use to which the heater is applied.

24 represents a pipe line from a source of fuel supply which is directed to the pump chamber 28 in the pump 19 from whence it travels through 10 the pipe 26, the metering valve 27, the pipe line 28 to the fuel heating coil 29, where it may be vaporized before it is delivered to the nozzle 30. 31 represents a priming tray for the nozzle 30.

15 The displacement pump 19 may be of the type disclosed in my application for Letters Patent Serial No. 87,847, filed June 29, 1936. The burner structure may be of the character disclosed in my application for Letters Patent Serial No. 91,405 20 filed July 18, 1936.

32 represents a gauge in the fuel line 28 for indicating the pressure therein. 33 represents a pressure indicating gauge in the discharge line 23 of the heater. 34 represents a control line 25 connected to the discharge line 23 for transmitting temperature and/or pressure intelligence to the controller 35, which accordingly operates the pump motor 36 through the contactor 37.

As disclosed above, the heating coils 12 and 14 30 may be wound in the form of a helix. However, when they are mounted within the combustion chamber they should be disposed at an angle so that the lowest portion of each coil turn is below the juncture between the next adjacent coil turns 35 thereabove and therebelow. This is illustrated in the drawing wherein the front passes 38 of the coil turns are shown in section in Fig. 2 and the rear passes 39 of the coil turns are shown in section in Fig. 3. Each of these views demonstrate 40 that the lowermost portion 40 of each coil turn is filled with liquid as indicated at 41 and the uppermost portion or the juncture between each coil turn is filled with steam or vapor of the liquid as indicated at 42.

45 Thus each turn of the heater coils represents a small boiler when the fluid is not flowing through the coil. This condition is set up within the heating coils when the discharge through the pipe 23 is stopped or throttled sufficiently to permit 50 an increase in pressure at the discharge of the heater. This intelligence is transmitted through 34 to the controller 35, which may select through the contactor 37 to stop or reduce the speed of the pump motor and thereby stop or reduce the flow 55 of fluid and its proportionate amount of fuel which decreases the pressure.

If the temperature of the emulsion in the discharge pipe 23 is excessive, the controller 35 will operate the contactor 37 to stop or reduce the flow 60 of fuel and fluid to the heating coil.

If the flow of the fluid emulsion is reduced or stopped within the heating coils sufficiently to permit the emulsion to separate into steam or vapor and the liquid as indicated; and subsequently the flow is reestablished or increased, an emulsion of the steam or vapor with the liquid would be formed immediately by reason of the series of traps. This would not be true if the steam or vapor of the system were permitted to 65 collect in one large body within the heater as in the case of an ordinary steam boiler.

70 By controlling the metering of the fluid and the fuel and with the provision of these traps, I am enabled to maintain the proper consistency of 75 the parts forming the emulsion. Thus I may

produce a mixture of a liquid and saturated steam or vapor or steam and vapor of a liquid in proper proportions. These results can not be obtained by the conventional steam boiler, or the like.

5 Referring to Fig. 4, 43 represents the lead heating coil connected to the pipe 22 as shown at 44. The upper end of the coil 43 is connected to the three-way block or fitting 45, which in turn is connected to the upper end of the coils 46 and 47. The lower end of the coil 46 is connected at 48 10 to the pipe 49 which traverses the bottom of the combustion chamber and is connected to the lower end of coil 47 as shown at 50, and passes thence to the discharge pipe 23.

Thus the fluid travels up the coil 43 where it separates and travels down the coils 46 and 47. As the fluid travels up the coil 43 it is being heated and therefore expands and the return coils 46 and 47 provide the additional space to compensate for such expansion. When two coils are employed as illustrated in Fig. 1 the return coil 14 15 may be formed with tubing having a larger internal opening than that of coil 12 to provide for the expansion of the fluid. This disclosure is similar to that shown and described in my Patent 20 No. 1,925,643, issued September 5, 1933.

25 It should be noted that the coils 43, 46 and 47 are each tilted to an angle that will provide a trap in each coil turn as illustrated in Figs. 2 and 3.

30 To stiffen the coils and maintain their coil turns in proper spaced relation it is convenient to provide the bracing members 51 which are secured at their lower ends to the base ring 11 and extend along the perimetral surface of the coil 35 turns. It may be found necessary to secure only the top coil turn to the brace 51, as indicated at 52. The coil turns may be secured to the brace as by strapping, silver-soldering, welding or other suitable means. Again additional support may 40 be given to the coils by suspending the blocks 13 and 45 from the upper part of the combustion chamber as indicated at 53 in Fig. 1.

45 The size of the tubing opening and the diameter of the helical heating coils are the material 45 dimensions for determining the pitch that these coils must assume to provide a series of traps therethrough. The helical coil is unquestionably the simplest and most economical to manufacture. However, a series of traps could be 50 formed by bending the tubing in corrugated waves as the coil is being wound and it would not be required to have a batter to produce the traps. Again I may employ a series of horizontal tubes having traps intermediate of their 55 ends. These tubes may terminate in headers to provide multiple passes across the combustion chamber.

60 As a preferred form I have shown and described a helical coil arranged within the combustion chamber to permit each spaced coil turn to function as a trap. The angular disposition of these helical coils within the combustion chamber prevents the flame from traveling in a straight path therethrough. The burning fuel 65 passes through the spaces between the coil turns as it travels up the combustion chamber toward the stack. Thus a simple helical coil which is economical to manufacture serves to provide traps along the conduit carrying the fluid to be 70 heated and also provides baffling, thereby producing a more efficient heat transfer agent.

75 Where the expression "mixture" is used in the claims I mean a liquid solution including water, steam, and a gaseous substance that has the 75

characteristics of both. The gaseous substance is frequently referred to as wet or saturated steam but it may include vapors of soluble substances derived from the solution fed to the heating coils.

5 I claim:—

1. In apparatus for producing a spray composed of a mixture of a liquid, a vapor of a liquid and steam of a liquid, the combination of 10 a tube, means for supplying a predetermined amount of liquid to said tube, means for supplying fuel to said tube for heating said liquid at a rate so correlated with the rate of supplying liquid as to produce a predetermined ratio between the elements of the mixture, and a plurality of traps arranged along said tube for collecting relatively small portions of the mixture during the stoppage or retardation of the travel of the liquid to prevent a material segregation 15 of the elements of the mixture.

15 2. In apparatus for producing a spray composed of a mixture of a liquid, a vapor of a liquid and steam of a liquid, the combination of an inclined tube, means for supplying a predetermined amount of liquid to said tube, means for supplying fuel to said tube for heating said liquid at a rate so correlated with the rate of supplying liquid as to produce a predetermined ratio between the elements of the mixture, and 20 a plurality of traps arranged along said tube for collecting relatively small portions of the mixture during the stoppage or retardation of the travel of the liquid to prevent a material segregation of the elements of the mixture.

25 3. In apparatus for producing a spray composed of a mixture of a liquid, a vapor of a liquid and steam of a liquid, the combination of a helical tube, means for supplying a predetermined amount of liquid to said tube, means for 30 supplying fuel to said tube for heating said liquid at a rate so correlated with the rate of supplying liquid as to produce a predetermined ratio between the elements of the mixture, and a plurality of traps arranged along said tube for collecting relatively small portions of the mixture during the stoppage or retardation of the travel of the liquid to prevent a material segregation 35 of the elements of the mixture.

4. In apparatus for producing a spray composed of a mixture of a liquid, a vapor of a liquid and steam of a liquid, the combination of a helical tube, means for supplying a predetermined amount of liquid to said tube, means for supplying fuel to said tube for heating said liquid at a rate so correlated with the rate of supplying liquid as to produce a predetermined ratio between the elements of the mixture, said helical tube being disposed at an angle to the vertical 10 to trap relatively small portions of the mixture during the stoppage or retardation of the travel of the liquid to prevent segregation of the elements of the mixture.

15 5. In apparatus for producing a spray composed of a mixture of a liquid, a vapor of a liquid and steam of a liquid, the combination of a plurality of helical heating coils, means for supplying a predetermined amount of liquid to said coils, means for supplying fuel to said coils for heating said liquid at a rate so correlated with the rate of supplying liquid as to produce a predetermined ratio between the elements of the mixture, and the axes of said coils being disposed on non-intersecting inclined axes to provide a plurality of traps for collecting relatively small portions of the mixture during the stoppage or retardation of the travel of the liquid to prevent a material segregation of the elements 20 of the mixture.

25 6. In apparatus for producing a spray composed of a mixture of a liquid, a vapor of a liquid and steam of a liquid, the combination of a tube, means for supplying a predetermined amount of liquid to said tube, means for supplying fuel to said tube for heating said liquid at a rate so correlated with the rate of supplying liquid as to produce a predetermined ratio between the elements of the mixture, means actuated by the temperature of the mixture prior to its discharge as a spray for simultaneously stopping and starting the supply of liquid and fuel to said tube, and a plurality of traps in said tube for segregating relatively small portions of the mixture when its movement is retarded or 30 stopped within the tube.

FRANK W. OFELDT.
